UNITED STATES PATENT OFFICE.

JAMES P. TOLMAN, OF NEWTON, MASSACHUSETTS, ASSIGNOR TO SAMSON CORDAGE WORKS, OF BOSTON, MASSACHUSETTS, A CORPORATION OF MASSACHUSETTS.

TWINE-PACKAGE.

1,135,470.

Specification of Letters Patent. Patented Apr. 13, 1915.

Application filed July 15, 1912. Serial No. 709,360.

To all whom it may concern:

Be it known that I, JAMES P. TOLMAN, of Newton, in the county of Middlesex and State of Massachusetts, a citizen of the 5 United States, have invented a new and useful Improvement in Twine-Packages, of which the following is a specification.

My invention relates to the packaging of twine and is more especially adapted to the 10 packaging of glazed twine where the package is not on a spool with flanges to protect the ends of the package. Glazed twine is given a smooth glazed finish in its manufacture and as a result when wound into a 15 package for sale the several layers are apt to slip off from one another especially after a portion of the twine has been unwound. As a result the twine is apt to become tangled and the package not only becomes 20 unsightly, but waste of material is occasioned. My invention is intended to overcome this difficulty and comprises a package in which the twine is caught or stuck by paste or the like at different points along 25 its entire length in such manner that under ordinary conditions it will be held in place, but may be unwound on a very slight pull. In the forms of packages shown in the drawings this is accomplished by applying a coat 30 of paste to one or both ends of the package so that the paste will permeate the spaces between the layers of twine and when dry attach them lightly together the end of the package comprising what may be termed a 35 wall built up of twine and paste, the paste serving merely to connect the ends of the several layers together. A very slight pull on the twine will free it.

In the drawings I have shown several 40 forms of package in each of which my invention is embodied, but I do not mean to limit the application of my invention to the forms shown nor to glazed twine alone.

Figure 1 is a perspective view of a package 45 embodying my invention. Figs. 2 and 3 are perspective views of packages of different shapes also embodying my invention.

A is the package and B is the layer of

paste applied to its end, C being the tube on which twine is sometimes wound. Any 50 ordinary paste such as commercial size or starch or flour paste may be used, and it may be applied by an ordinary paste brush, a single application of the brush full of paste to each end of the package giving a sufficient 55 coating to the ends of the package to cause the layers of twine to adhere. In some cases where the character of the glaze on the twine permits it, the wetting of the ends of the package will dissolve the glaze sufficiently 60 so that the glaze of one layer will merge with the glaze on the next and when dry the layers will adhere to each other at the ends of the package. Of course but little adhesion between the layers of twine 65 will be necessary, only sufficient to prevent them from falling apart under ordinary usage and until they are pulled apart when a supply is being drawn off the package for 70 use.

By ordinary usage I refer to the fact that the package when broken for use is sometimes mounted on a spindle on which it rotates as the twine is drawn off, sometimes placed in a receptacle or cagelike structure 75 which holds it in place, and sometimes thrown loosely in a drawer from which the end of the package hangs. In any of these cases the package is kept intact by the paste so that the twine will not fall off from it, but 80 will be drawn off layer by layer as its use may require. When the paste is dry the various layers will be held together sufficiently firmly for the purpose referred to.

What I claim as my invention is:— 85

A cross-wound package of non-cohering or glazed twine the several turns or layers of which are caught together at separated points by a superficial coating of adhesive material applied to one or both ends of said 90 package.

JAMES P. TOLMAN.
